MASSACHUSETTS, A CORPORATION OF MASSACHUSETTS.

PAPER-MAKING MACHINE.

Application filed October 29, 1921. Serial No. 511,340.

To all whom it may concern:

Be it known that we, JOHN W. VEDDER and FREDERICK W. LODDING, residents of Worcester, Massachusetts, and citizens of the United States, have invented new and useful Improvements in Paper-Making Machines, which invention is fully set forth in the following specification.

This invention relates to the Fourdrinier or wire part of paper making machines. In many mills, in the making of news print paper (which may be of low grade or quality because it is only for temporary use) it is common practice to dispense entirely with shaking of the wire. But for higher grades of paper the usual lateral shaking of the wire is still resorted to by the use of structures in which the shaking or vibration is imparted to a long and heavy frame, to the breast roll, numerous wire supporting table rolls, guide rolls and other parts all mounted on said frame, and to the wire itself running over said rolls, said shaken parts aggregating great mass and weight. The repeated starting and stopping of such mass and weight of parts, once for each vibration, involves great strain, requires additional weight to attain requisite strength of structure, occasions considerable wear and deterioration of parts with resulting increase in cost of maintenance or upkeep, and also occasions complications of parts and structure adding to the time and effort required in replacements of the wire, each wire lasting only from one to three weeks in a machine running regularly at normal capacity. In such structures the full length of the lateral shaking stroke imparted to the end of the frame at which the breast roll is carried, gradually diminishes in amplitude toward the other end of the frame which practically turns about or pivots on a vertical axis. While the full force and width of the shaking stroke at and in the vicinity of the breast roll is desirable and necessary to thoroughly interweave the fibers of the pulp mixture delivered on to the wire, the attenuated diminution in amplitude of stroke until it becomes practically nil at the far end

of the long vibrating frame and long series of table rolls carried thereby, acts to a material extent to straighten out the fibers of the sheet and to thus undo the previously attained interweaving of said fibers. In other words, approximately as good and possibly better paper formation may be attained by shortening the shaking length of wire.

The primary object of this invention is to provide a machine in which a relatively short length of the wire at the receiving end thereof will be shaken or laterally vibrated, to avoid attenuated gradual diminution of shake or vibration extending far down the wire from the receiving end thereof, and to accomplish this in a manner dispensing with large mass and weight of shaking parts and eliminating strain and rapid wear, and to thus simplify the mechanism and effect a material saving not only in the initial cost thereof but in expense of maintenance or upkeep of apparatus.

The aforesaid and other objects and advantages which will become apparent from the detailed description are accomplished by the structure of this invention, a preferred embodiment of which is illustrated in the accompanying drawings, wherein—

Figs. 1 and 1^a are together a side elevation of the Fourdrinier part of the machine; 80

Fig. 2 is an elevation looking toward the right on line 2—2 of Fig. 1 with some parts above the breast roll omitted;

Fig. 3 is a plan view showing the breast roll and the first section of table rolls and associated parts of the non-shaking framework of Fig. 1; 85

Fig. 4 is a vertical sectional view through a part of the mechanism at one side of the machine for changing the elevation of the breast roll end of the frame carrying said roll, the table rolls, and other parts; 90

Fig. 5 is a detail front elevation of the right hand end of a transversely extending U-beam constituting part of the roll carrying frame;

Fig. 6 is a detail sectional view on line 6—6 of Fig. 1^a;

Figs. 7 are detail views of one of the bearing members for the breast roll;

Fig. 8 is a fragmentary side elevation showing a modified structure in which the elevation of the apron of the flow box is automatically adjusted with changes in the elevation of the breast roll end of the roll carrying frame; and

Fig. 9 is a fragmentary plan view, similar to the left hand end of Fig. 3, but showing a modified structure in which none of the table rolls are to be vibrated the shake of the wire resulting from vibration of the breast roll only.

Referring first to Figs. 1 to 6 inclusive—to provide for changing the elevation of the Fourdrinier wire at the receiving end thereof and to thereby attain the desired pitch or inclination of said wire from its receiving toward its delivery end, we employ a frame carrying most of the rolls on which the wire runs, said frame being vertically adjustable at its end toward the flow box and supported at its other end to turn on a horizontal axis or pivots. Said frame is made up of the following parts—at the end thereof next to the flow box there is a transversely positioned beam 11 of elongated U-shape having at its opposite ends respectively upstanding arms 12 and 13 of hollow construction. 14 is a longitudinally extending top rail at one side of the frame secured at one end by bolts 15 to the top of arm 13 of beam 11 and secured at its other end by a bolt 16 to a plate 17 which fits on a block 18, said block depending between two ears 19 and 19 at the upper end of a supporting post or standard 20 and said ears and block being traversed by a horizontal pivot pin 21, such structure being similar to that illustrated in Figs. 6 and 7 of Patent No. 1,118,366, dated Nov. 24, 1914, to Mellinger, et al. A longitudinally extending top rail 22 (similar to 14) at the other side of the machine is secured at one end by bolts 23 to the top of arm 12 of beam 11 and at its other end is pivotally supported at the top of a post or standard (not shown) similar to standard 20 by means similar to those described and illustrated in Fig. 6 with reference to top rail 14. In order to truss and stiffen the top rail 14 we provide a suitable strut bar 24 extending parallel thereto. At one end bar 24 is connected to the upright arm 13 of beam 11 through the intermediary of an angle bracket 25. An upwardly curved arm 26 is rigidly bolted to the other end of bar 24 said arm at its upper end being traversed by and pivoted on the before mentioned pivot pin 21 as shown in Fig. 6. Intermediate of its ends the bar 24 is rigidly connected to the rail 14 by an upright brace 27. The bar 24, angle bracket 25, arm 26, and upright brace 27, are du-

plicated at the other side of the machine in connection with the top rail 22. To rigidify and brace the frame in a transverse direction we provide two brace rods 28, 28, extending from the bar 24 across the machine to the corresponding bar at the other side thereof and passing through lugs of plates 30 bolted to said bars as shown in Fig. 1. There is thus constituted an elongated rigid frame horizontally pivoted and supported at one end on the pivot pins 21 and at its other end next to the flow box adapted to be adjusted to varying elevations to attain the desired pitch or inclination of the Fourdrinier wire at its receiving end.

The table rolls are shown as arranged in three groups or series, 31, 32 and 33 respectively. An angle bar 34 supported from rail 14 by brackets 35 and 36 (Figs. 1 and 1^a) and a similar angle bar supported by similar brackets from the rail 22 at the other side of the machine, but not shown in the drawings, carry bearings of well known construction (such for example as shown in patent to John Stoddard 1,129,916, March 2, 1916) in which the opposite ends of the table rolls 33 are journaled. The series of table rolls 32 are similarly supported in bearings carried by an angle plate 37 supported from rail 14 by brackets 38 and 39 and by a similar angle plate supported by similar brackets from the rail 22 at the other side of the machine. The series or group of table rolls 31 are supported in bearings carried by angle bars 40 and 41 respectively at opposite sides of the machine, see Fig. 3. Since the series of table rolls 31 is to be shaken the angle bar 40 is pivotally supported at one end from rail 14 by a bracket 42 and angle bar 41 likewise pivotally supported at one end from rail 22 by a bracket 43. The supporting of the other ends of angle bars 40 and 41 will be described presently. 45 is the breast roll which is supported in a manner admitting of the imparting of shaking movement to it and its supporting bearings without vibration of the frame hereinbefore described or other part of the main framework of the machine. At each end of breast roll 45 the shaft thereof rests in an open sided bearing member 46 as shown in Figs. 1, 3 and 7. The bearing surface of said member is grooved to receive enlargements or ribs 47 extending around the projecting shaft end, whereby shaking movement imparted to either of said bearing members will be transmitted to the breast roll and through it to the other bearing member 46.

A flat steel spring bar 48, at the right hand side of the machine, Fig. 2, is securely bolted at its upper end in a slot of a link 49 the latter being pivoted by a pin 50 in a slot be-

tween ears 51 (Fig. 7) on the underside of the bearing member 46; but if preferred said upper end of the spring may be rigidly secured to bearing member 46, for example, 5 in the manner the upper end of the corresponding spring of the aforesaid Mellinger et al. patent is secured. Said spring 48 at its lower end is seated in an upwardly opening notch or slot 52 of a stirrup or bracket 10 53, Figs. 1, 2 and 5, depending from and preferably cast integral with the upright arm 13 of the beam 11. By such arrangement said bearing 46 is movably supported by the spring 48 with the flat surface 54, 15 Fig. 7, thereof in engagement with a bearing plate 55, preferably of brass, which as shown in Fig. 5 may be detachably secured to the arm 12 by screws. The other bearing member 46 at the other side of the machine, 20 at the left in Fig. 2, is supported by similar means including a flat steel spring 56, link member 57, pivot pin 58, a notch or slot 59 engaged by the lower end of spring 56, said notch being formed in a stirrup or bracket 25 60 depending from arm 12 of the beam 11. In this instance also a flat face 54 of the bearing member 46 engages a brass plate detachably secured to the arm 12 and similar to the plate 55 hereinbefore described. The 30 projecting end of the pivot pin 58 is engaged by the end of a pitman or connecting rod 61, Fig. 2, driven from any suitable source of power (not shown) to impart vibrating or shaking movement to the bearing member 35 46 at the left of Fig. 2 and thence to the breast roll 45 and through it to bearing member 46 at the other side of the machine. An arm 62, secured at one end to the bearing member 46 at the left in Fig. 2 by bolts 63, 40 bends rearward to a pivotal bolt connection at 64 to the forward end of the hereinbefore described angle bar 41, said arm thus serving both to support said end of bar 41 and to impart vibrating or shaking movement thereto 45 around the pivotal support at the rear end of said bar. An arm 65 at the right of Fig. 2, similar to 62, secured by bolts 66 to the bearing member 46, also bends rearward to a pivotal bolt connection at 67 to the forward end of angle bar 40 hereinbefore described, said arm 65 thus serving both to support said end of bar 40 and to impart vibrating or shaking movement thereto around the pivotal supporting connection at 50 55 the rear end thereof. Such lateral vibration or shaking of the bars 40 and 41, simultaneously with the similar movement of the breast roll 45, also imparts endwise shaking movement to the series of table rolls 31 extending between and supported by said bars. 55 To prevent vibration of the hereinbefore described frame incident to the aforesaid shaking of the breast roll and the series of table rolls 31, two vertically depending plates 70, 70 are secured by bolts to the un- 60 derside of the U-beam 11, near opposite ends thereof respectively, each plate 70 fitting closely and slidably between the oppositely positioned vertical surfaces of a pair of brackets 71 bolted to a transverse base beam 70 72, Fig. 2. Thus while the plates 70 permit vertical movement or adjustment of the breast roll end of the frame in changing the pitch of said frame and of the Fourdrinier wire carried by the rolls thereof, said plates 70 rigidly secure said frame against lateral vibration incident to the shaking of the breast roll and other parts. 75 73, 74, 75 Fig. 1 and Fig 1^a are carrying rolls for the Fourdrinier wire suitably mounted through the intermediary of suitable bearings (not shown) at opposite ends of said rolls, on the bars 24 at opposite sides of the machine, or on the frame of which said bars constitute parts. 76, 77 and 78, 80 Fig. 1^a are other carrying rolls for the wire suitably supported and journaled in well known manner not illustrated. 79 is the lower couch roll also suitably supported and journaled in well known manner not illustrated and over which the wire runs at one end of its path of travel. 80 is the endless Fourdrinier or making wire running over the aforesaid rolls and passing at one end around the breast roll 45, the pull on said wire serving to hold the projecting ends of the shaft or axle of the breast roll firmly seated in the open sided bearing recesses of the two bearing members 46, 46, respectively. 85 81, 81 are two save-all receptacles each 100 extending across the machine beneath the table rolls and wire thereon and resting at opposite ends on rollers 82 journaled in supports 83 secured to bar 24 and to the corresponding bar at the other side of the machine. Suitably supported roofs 84, each resting at one edge on an edge of one of the save-all receptacles 81, serve the usual purpose of draining into said receptacles liquid falling thereon from the pulp mixture delivered on to the wire. These save-all receptacles and roofs being thus mounted upon and carried by the frame participate in any vertical adjustment of said frame in changing the pitch of the wire. The save-all receptacles and roofs may however be supported independently of the frame so as not to participate in adjustments thereof. 105 110 115 Vertical adjustment of the breast roll end of the aforesaid frame is effected by the following means:—The upright arms 12 and 13 of the U-beam 11 are each formed with a downwardly opening socket 85 having a bearing block 86 of hardened metal secured in the upper end thereof and provided with 120 a downward opening semispherical bearing recess or socket. A tubular supporting member 87 extends upwardly into said socket 85 and has secured to its upper closed end a bearing block 88 of hardened metal 125 130

- having an upwardly projecting semispherical knob engaging the corresponding socket of block 86, as best shown in Fig. 1. At its lower end the member 87 rests and is held by the weight of parts in a seat 89, Fig. 4, of a casing formed in two parts 90 and 91 detachably held together by bolts 92 and serving to enclose antifriction ball bearings and gears about to be described.
- 10 An upright support, post, or bar 95 is horizontally pivoted at its lower end at 96 in a base block 97 rigidly secured to the floor or other foundation on which the machine is mounted. The upper screw-threaded end 15 of bar 95 extends upward through the two part casing 90—91 and into the tubular member 87, as best shown in Figs. 1 and 4. A worm gear 98, housed within the two part casing 90—91, has an elongated interior screw-threaded hub through which the screw-threaded portion of bar 95 engages. Three sets of antifriction or ball bearings, shown in Fig. 4, are interposed between the worm gear 98 and its two part enclosing casing to take the vertical and side stresses of the supported load and to provide for free and easy rotation of said worm gear in raising or lowering the frame and parts carried thereby to change the pitch of the wire.
- 20 The balls 100 of the lowermost set of bearings work between a ring 101 surrounding the lower end of the hub of the worm gear and a ring 102 secured within the casing member 91. An annular plate 103 is secured by screws to the underside of casing 91 and carries a packing ring 104 of leather or other suitable material closely fitting around the peripheral surface of the lower extremity of the hub on the worm wheel to prevent leakage of lubricant. The balls 105 of the next set of ball bearings work between a ring 106 surrounding the part of the hub projecting upward from the top side of the worm gear and a ring 107 secured in the upper casing member 90. The balls 108 of the uppermost set of ball bearings, which set takes the stress of the vertical load, work between a ring 109, located at the top of casing member 90 and surrounding the upper end of the hub of worm wheel 98, and a ring 110 also surrounding said upper end of the hub and separated from the before mentioned ring 106 by an interposed ring 111. A worm 112, also housed within the two part casing 90—91, engages the worm wheel 98 and is secured to a horizontal shaft 113 which has bearings in said two part casing at opposite sides of said worm. Said shaft 113 extends all the way across the machine and carries at each end thereof a hand wheel 114 as best shown in Fig. 2.
- It is to be understood that the tubular support member 87, the two part casing 90—91, the upright pivoted screw-threaded
- support bar 95, and the ball bearings, worm wheel 98, worm 112, and other associated parts illustrated in Figs. 1 and 4 in connection with upright arm 13, are all duplicated at the other side of the machine in 70 connection with the upright arm 12 and its downwardly opening socket, the shaft 113 being common to the two worms 112, 112 at opposite sides of the machine. As will thus be apparent, rotation of said shaft by 75 gripping and turning either of its hand wheels 114, acting through the two worms 112, 112, on said shaft will rotate the two worm wheels in engagement with the two screw-threaded support bars 95 at opposite 80 sides of the machine and thereby raise or lower the supporting frame uniformly at both sides of the machine according to the direction in which the hand wheel 114 is turned.
- 85 Referring particularly to Figs. 1 and 1^a, 120 is a deckle strap running over a deckle wheel 121 at one end, Fig. 1, and deckle pulley 122 at its other end, Fig. 1^a, and passing through deckle wash trough 123 supported on a deckle frame 124 shown as supported from the side rail 14 by brackets 125, 125, all these parts being of well known construction and duplicated at opposite sides of the machine.
- 90 Flow box 130, shown in Fig. 1, may be of any well known suitable construction, with a delivery opening at its front side the lower edge of which is indicated at 131 by dotted line, and provided with a suitable 100 apron 132 adapted to be vertically adjusted to the desired position relative to the elevation of the wire and to the delivery opening of the flow box by means of a screw 133 adapted to be rotated by hand wheel 134 through beveled gears 135 and 136, Fig. 1. Fig. 8 illustrates a modified structure in which the elevation of the apron 132 is automatically adjusted to follow changes in the elevation of the receiving end of the wire, 110 this being accomplished through the following connections which are preferably duplicated at opposite sides of the machine, to wit—140 is an arm secured to, or it may be cast integral with, the stirrup member 53 115 and extending therefrom toward the flow box. A link 141 is pivotally connected at its lower end to said arm 140 and at its upper end to a lug 142 secured to the apron 132. It follows that any up or down movement imparted to the frame carrying the wire and rolls over which it runs will be transmitted through said connections to the apron 132.
- 120 Fig. 9 illustrates a modified structure in 125 which the series of table rolls 31, instead of being shaken or vibrated along with the breast roll 45 as in the structure illustrated in the other figures of the drawings, are not shaken, and are moved endwise, if at all, 130

only in so far as the freedom of their bearings permit and such movement is imparted thereto by the wire resting thereon. As shown in said Fig. 9, there is no shake transmitting

5 arm such as 62 connecting one end of the angle bar 41 to the bearing 46, but on the contrary said bar is rigidly secured to and supported at both ends from the rail 22 by the brackets 43, 43 shown in dotted lines. The angle bar at the other side of the machine corresponding to 41 is similarly arranged and rigidly connected at both ends to the rail at that side of the machine corresponding to 22.

10 15 What we claim is:—

1. In a paper making machine, a Fourdrinier wire, a frame carrying suitable rollers including a breast-roll on which said wire runs, means supporting said frame whereby its position may be altered to change the pitch or inclination of the wire, means supporting said breast-roll from said frame so that said roll may have endwise shaking movement relative to said frame, and means 20 25 imparting endwise shaking movement to said breast-roll relative to said frame and thereby shaking the wire with said roll.

2. In a paper making machine, a Fourdrinier wire, a frame carrying suitable rollers 30 including a breast-roll on which said wire runs and said frame being adapted to be raised and lowered at one end on pivotal supporting means at its other end to change the pitch or inclination of the wire, means 35 supporting said breast-roll from said frame so that said roll may have endwise shaking movement relative to said frame and means imparting endwise shaking movement to said breast-roll relative to said frame and thereby shaking the wire with said roll.

40 3. In a paper making machine, a Fourdrinier wire, a frame carrying suitable rollers including a breast-roll on which said wire runs, means supporting said frame including adjustable means adapted to raise and lower said frame at one end thereof to thereby change the pitch or inclination of the wire, means supporting said breast-roll from said frame so that it may have endwise shaking movement relative to said frame, and means imparting endwise shaking movement to said breast-roll relative to said frame and thereby shaking the wire with said roll.

45 5. In a paper making machine, a Fourdrinier wire, a frame carrying suitable rollers including a breast-roll on which said wire runs, means supporting said frame whereby its position may be altered to change the pitch or inclination of the wire, means supporting said breast-roll from said frame said means including bearings at opposite ends of the roll movably attached to said frame so that said roll and its said 60 65 bearings may have endwise shaking move-

ment relative to said frame, and means imparting endwise shaking movement to said breast-roll and its bearings and thereby shaking the wire with said roll.

5. In a paper making machine, a Fourdrinier wire, a frame carrying suitable rollers including a breast-roll on which said wire runs, means supporting said frame whereby its position may be altered to change the pitch or inclination of the wire, 70 means supporting said breast-roll from said frame said means including bearings at opposite ends of the roll and spring bars movably supporting said bearings from said frame so that by the yielding thereof 80 said roll and its bearings may have endwise shaking movement relative to said frame, and means imparting endwise shaking movement to said breast-roll and its bearings and thereby shaking the wire with said 85 roll.

6. In a paper making machine, a Fourdrinier wire, a frame carrying suitable rollers including a breast-roll on which said wire runs, means supporting said frame whereby its position may be altered to change the pitch or inclination of the wire, means supporting said breast-roll from said frame said means including bearings at opposite ends of the roll movably supported 90 upon said frame to make endwise sliding engagement therewith, and means imparting endwise shaking movement to said breast-roll and its bearings relative to said frame and thereby shaking the wire with said roll. 100

7. In a paper making machine, a Fourdrinier wire, a frame carrying suitable rollers including a breast-roll on which said wire runs said frame including an approximately U-shaped beam across one end 105 thereof, means supporting said frame whereby its position may be altered to change the pitch or inclination of the wire, means supporting said breast-roll from said frame said means including bearings at opposite ends of the roll movably supported 110 upon said beam to make endwise sliding engagement therewith, and means imparting endwise shaking movement to said breast-roll and its bearings relative to said frame 115 and thereby shaking the wire with said roll.

8. In a paper making machine, a Fourdrinier wire, a frame carrying suitable rollers including table-rolls and a breast-roll on which said wire runs, means supporting said frame whereby its position may be altered to change the pitch or inclination of the wire, means supporting said breast-roll and a group or section of table-rolls 120 upon said frame so that the same may have endwise shaking movement relative to said frame, and means imparting endwise shaking movement to said breast-roll and said table-rolls relative to said frame and thereby shaking the wire with said rolls. 125 130

9. In a paper making machine, a Four-drinier wire, a frame carrying suitable rollers including table-rolls and a breast-roll on which said wire runs, means supporting said frame whereby its position may be altered to change the pitch or inclination of the wire, means supporting said breast-roll and a group or section of table-rolls upon said frame so that the same may have endwise shaking movement relative to said frame, said supporting means including bearings at opposite ends of said breast-roll and table-rolls also adapted to move endwise relative to said frame, and means imparting endwise shaking movement to said breast-roll and said table-rolls and their supporting bearings relative to said frame and thereby shaking the wire with said rolls. 65
10. In a paper making machine, a Four-drinier wire, a frame carrying suitable rollers including table-rolls and a breast-roll on which said wire runs, means supporting said frame whereby its position may be altered to change the pitch or inclination of the wire, means supporting said breast-roll from said frame so that the same may have endwise shaking movement relative to said frame, means supporting a group or section of table-rolls from said frame so that the same may have endwise shaking movement relative to said frame said means including two bars pivotally mounted on said frame and carrying bearings for the opposite ends of said table-rolls respectively, and means imparting endwise shaking movement to said breast-roll relative to said frame and vibrating said bars on their pivotal mountings to impart endwise shaking movement to the table-rolls carried thereby relative to said frame, the shaking of said breast-roll and table-rolls also imparting shaking movement to the wire in contact therewith. 80
11. In a paper making machine, a Four-drinier wire, a frame carrying suitable rollers including table-rolls on which said wire runs, means supporting said frame whereby its position may be altered to change the pitch or inclination of the wire, means supporting a group or section of table-rolls upon said frame to have endwise shaking movement relative to said frame, and means imparting endwise shaking movement to said group of table-rolls relative to said frame. 85
12. In a paper making machine, a Four-drinier wire, a frame carrying suitable rollers including table-rolls on which said wire runs, means supporting said frame including adjustable means for raising and lowering the frame at one end thereof to change the pitch or inclination of the wire, means supporting a group or section of table-rolls upon said frame to have endwise shaking movement relative to said frame, 65
13. In a paper making machine, a Four-drinier wire, a frame carrying suitable rollers including table-rolls on which said wire runs, means supporting said frame including adjustable means for raising and lowering the frame at one end to change the pitch or inclination of the wire, means supporting a group or section of table-rolls upon and to have endwise shaking movement relative to said frame said means including two bars extending along opposite ends respectively of said group of table-rolls said bars carrying bearings for said rolls and each bar being pivoted at one end to said frame, and means for laterally vibrating the said bars on their pivots and thereby imparting endwise shaking movement to said bearings and table-rolls relative to said frame. 70
14. In a paper making machine, a frame including two approximately parallel rails at opposite sides thereof, two approximately parallel bars pivoted to said rails respectively, table-rolls extending between and journaled in bearings carried by said bars, means vibrating said bars on their pivots and thereby imparting endwise shaking movement to said bearings and the table-rolls journaled therein, and a Fourdrinier wire running over said rolls. 90
15. In a paper making machine, a frame including two approximately parallel rails at opposite sides thereof, two approximately parallel bars pivoted to said rails respectively, table-rolls extending between and journaled in bearings carried by said bars, means vibrating said bars on their pivots and thereby imparting endwise shaking movement to said bearings and the table-rolls journaled therein, a Fourdrinier wire running over said rolls, and means supporting said frame and adjustable to change the position of the frame to increase or decrease the pitch or inclination of the wire. 100
16. In a paper making machine, a frame including two approximately parallel rails at opposite sides thereof, table-roll bearings movably mounted upon and supported by said frame, table-rolls journaled in said bearings and positioned between said rails, a Fourdrinier wire carried by said frame and running on said rolls, and means imparting endwise shaking movement to said bearings and rolls relative to said frame. 115
17. In a paper making machine, a frame including two approximately parallel rails at opposite sides thereof, table-roll bearings movably mounted upon and supported by said frame, table-rolls journaled in said bearings and positioned between said rails, 120
- 125

- a Fourdrinier wire carried by said frame and running on said rolls, means imparting endwise shaking movement to said bearings and rolls relative to said frame, and means supporting said frame and adjustable to change the position of the frame to increase or decrease the pitch or inclination of the wire. 65
18. In a paper making machine, a frame including two approximately parallel rails at opposite sides thereof, table-roll bearings movably mounted upon and supported by said frame, table-rolls journaled in said bearings and positioned between said rails, breast-roll bearings movably mounted upon and supported by said frame, a breast-roll journaled in said bearings, a Fourdrinier wire running over said breast-roll and table-rolls, and means imparting endwise shaking movement to said breast-roll and table-rolls and their bearings relative to said frame. 70
19. In a paper making machine, the combination of a Fourdrinier wire, a frame, suitable rollers carried by said frame on which said wire runs, means for raising and lowering said frame at one end to thereby change the pitch or inclination of said wire said means including an upright post, a wheel making screw-thread engagement with said post and supporting said frame on said post, and means operable to rotate said wheel and thereby raise or lower the frame. 75
20. In a paper making machine, the combination of a Fourdrinier wire, a frame, suitable rollers carried by said frame on which said wire runs, means for raising and lowering said frame at one end to thereby change the pitch or inclination of said wire said means including an upright post pivotally supported at its lower end on a horizontal axis and adapted to change its position on said axis with changes in the elevation of the frame, a wheel making screw-thread engagement with said post and serving to support said frame on said post, and means operable to rotate said wheel and thereby raise or lower the frame. 80
21. In a paper making machine, the combination of a Fourdrinier wire, a frame, suitable rollers carried by said frame on which said wire runs, means for raising and lowering said frame at one end to thereby change the pitch or inclination of said wire said means including an upright post, a wheel making screw-thread engagement with said post and supporting said frame on said post, ball bearings interposed between the frame and said wheel, and means operable to rotate said wheel and thereby raise or lower the frame. 85
22. In a paper making machine, the combination of a Fourdrinier wire, a frame pivotally supported at one end and including in its construction an approximately U-shaped beam across the other end thereof each upright arm of said beam having a downwardly opening socket therein, suitable rollers carried by said frame and on which said wire runs, post-like supporting means at opposite sides of said frame and engaging upwardly in said sockets respectively, and means operable to lengthen or shorten said supporting means to raise or lower said end of the frame to thereby change the pitch or inclination of said wire. 90
23. In a paper making machine, the combination of a frame supported to be raised and lowered at one end thereof and including in its construction an approximately U-shaped beam across its other end each upright arm of said beam having a downwardly opening socket therein, a Fourdrinier wire carried by said frame, post-like supporting means at opposite sides of said frame each including two telescoping members one of which engages upwardly in one of said sockets, and means operable to relatively move said telescoping members to lengthen or shorten the supports for the frame and thereby raise or lower the frame at one end and change the pitch or inclination of the wire. 95
24. In a paper making machine, the combination of a frame supported to be raised and lowered at one end thereof and including in its construction an approximately U-shaped beam across said end each upright arm of said beam having a downwardly opening socket therein, a Fourdrinier wire carried by said frame, adjustable supports at opposite sides of the frame respectively each said support including in its construction a tubular member engaging upwardly in one of said sockets, a screw-threaded post member extending upwardly into said tubular member, and an adjustable member making screw-threaded engagement with said post member and supporting the tubular member on the post member, and means operable to rotate said adjustable member of each support to raise and lower the frame at one end and thereby change the pitch or inclination of the wire. 100
25. In a paper making machine, the combination of a frame, a Fourdrinier wire, suitable rolls carried by said frame on which said wire runs, means for imparting endwise shaking movement to one or more of said rolls relative to said frame, means for changing the elevation of one end of said frame to thereby change the pitch or inclination of the wire, a flow-box having a vertically movable apron, and a direct connection between said apron and said end of the frame imparting to the apron up and down movement of the frame. 105
26. In a paper making machine, the combination of a frame, a Fourdrinier wire, 110
- 120
- 125

suitable rolls journaled in bearings in said frame and on which said wire runs, means imparting endwise shaking movement to one or more of said rolls and their bearings relative to said frame, means for changing the elevation of one end of said frame to thereby change the pitch or inclination of the wire, a flow-box having a vertically

movable apron, and a direct connection between said apron and said end of the frame ¹⁰ imparting to the apron up and down movement of the frame.

In testimony whereof we have signed this specification:

JOHN W. VEDDER.

FREDERICK W. LODDING.
